(57) **CLAIM**

We claim the ornamental design for a cleaning pad, as shown and described.

DESCRIPTION

This Application is related to and incorporates herein by reference, in its entirety, pending U.S. patent application Ser. No. 09/689,433 filed Oct. 11, 2000 entitled advanced cleaning system, and claims any and all benefits to which it is entitled therefrom, which is related to and incorporates by reference, in its entirety, U.S. Provisional patent application Ser. No. 60/192,040 filed Mar. 24, 2000 entitled cleaning system, and claims any and all benefits to which it is entitled therefrom.

FIG. 1 is a bottom view of the cleaning pad showing our new design;

FIG. 2 is a top side view thereof;

FIG. 3 is a front side view thereof;

FIG. 4 is a rear side view thereof;

FIG. 5 is a right side view thereof;

FIG. 6 is a left side view thereof; and

FIG. 7 is a perspective rear, top, right side view of a cleaning head showing the apparatus and method of use of the cleaning pad of the present invention (unclaimed cleaning system structure being shown in broken lines); and, FIG. 8 is a perspective front, top, left side view of a cleaning system showing the apparatus and method of use of the cleaning pad of the present invention (unclaimed cleaning system structure being shown in broken lines).

The broken lines showing cleaning system environmental structure are for illustrative purposes only and form no part of the claimed design.
